UNITED STATES PATENT OFFICE

LE ROY W. FAIRCHILD, OF NEW YORK, N. Y.

DESIGN FOR PENCIL-CASES.

Specification forming part of Design No. **11,417**, dated September 16, 1879; application filed August 7, 1879.
[Term of patent 7 years.]

To all whom it may concern:

Be it known that I, LE ROY W. FAIRCHILD, of the city, county, and State of New York, have originated and designed a Case for Pencils, or other like implements, of which the following is a full, clear, and exact description, reference being had to the accompanying engraved illustration, making part of this specification.

The design consists in surrounding the tube or shell which contains the pencil or other implement with an ornament in the form of an hour-glass.

A represents the complete design, the pencil or other implement operating in the shell being retracted. b is the ring in the upper or stem end. c c c are ornamented beads, and d

d are the parallel bars or uprights, which extend over the double cone of the body and unite the two heads.

I do not, however, claim any specific ornamentation of the several parts which together make up the hour-glass form. These may be changed and variously ornamented.

What I claim is—

A design for a pencil-case in the form of an hour-glass, A, variously ornamented in its several parts, as shown by the ring b, the beads c c c, and the standards d d, substantially as hereinbefore set forth.

LE ROY W. FAIRCHILD.
